UNITED STATES PATENT OFFICE.

ELMER H. STOWELL, OF PONTIAC, MICHIGAN.

DESIGN FOR A HAT-HOLDER.

SPECIFICATION forming part of Design No. 35,246, dated October 29, 1901.

Application filed September 10, 1901. Serial No. 74,957. Term of patent 7 years.

To all whom it may concern:

Be it known that I, ELMER H. STOWELL, a citizen of the United States, residing at Pontiac, in the county of Oakland and State of Michigan, have invented and produced a certain new and original Design for Hat-Holders, of which the following is a specification, reference being had therein to the accompanying drawings, in which the design is shown in perspective.

A is an annulus.

B and C are frames arranged in planes substantially perpendicular to each other and to the plane of said annulus. Each of these frames comprises a central portion *a*, the portions *b* at either side thereof and bent at right angles thereto and the outwardly-bent end portions *c*, connecting at their ends with the annulus.

D is a helix connected at one end to the crossing portions *a* of the frames B and C and having its axis coincident with the axis of the annulus.

The leading feature of the design is the arrangement of the annulus, the frames, substantially as shown, and the central helix.

What I claim as my invention is—

The design for a hat-holder, substantially as herein shown and described.

In testimony whereof I affix my signature in presence of two witnesses.

ELMER H. STOWELL.

Witnesses:

C. B. TURNER,
G. W. FERRY.
